SHUTTLELESS LOOM FOR WEAVING FABRICS

Filed March 31, 1927

FIG. 1

FIG. 2.

UNITED STATES PATENT OFFICE.

HUGH LINLEY BYRD, OF STOCKPORT, ENGLAND, ASSIGNOR TO DREY, SIMPSON & COMPANY, LIMITED, OF SOUTH REDDISH, NEAR STOCKPORT, ENGLAND.

SHUTTLELESS LOOM FOR WEAVING FABRICS.

Application filed March 31, 1927, Serial No. 179,919, and in Great Britain April 6, 1926.

This invention has reference to looms of the kind known as shuttleless looms and in which the weft thread or threads is or are taken from a supply or supplies at one side or both sides of the loom and laid in the warp sheds by one or more weft inserters adapted to pass through, or be reciprocated into, the warp sheds.

The invention has for its object to provide improved means of presenting the weft or wefts to the weft-inserter or weft-inserters in such manner as to ensure the weft or wefts being engaged and taken by the weft-inserter or weft-inserters.

15 A weft-presenting means according to the invention comprises a weft guide or lifter mounted on the slay of the loom and adapted to be intermittently operated through the medium of ratchet, cam or equivalent mechanism and the movements of the slay so as to alternately interpose the weft in the path of the weft-inserter at the proper moment and afterwards carry the weft, or allow it to be carried or moved, clear of said path. The 25 weft guide or lifter may comprise only a single guiding or lifting member or it may comprise a plurality of such members adapted to operate in succession.

In the accompanying drawings Fig. 1 is 30 an elevation of a portion of the front of a loom and Fig. 2 is an elevation looking towards the right hand in Fig. 2 illustrating one embodiment of the invention.

The embodiment of the invention illustrated is particularly suitable in a loom in which the weft threads are inserted alternately from opposite sides of the loom by means of needles arranged one on each side of the loom and which pass into the warp sheds 40 and meet at or about the middle of same and then recede, the arrangement being such that a loop of weft carried into a shed by one of the needles is at the place of meeting transferred to the other needle which as it recedes 45 completes the laying of the weft in the shed.

Referring to the drawings, 3 is a shaft rotatably mounted across the slay 4 in bearings 5 and having fixed on it at each side of the loom a cam 6 having two cam surfaces 50 6^a, 6^b. The two cams are so fixed on the shaft 3 that the cam surfaces of one alternate with or are at 90° relatively to those of the other. At one end the shaft 3 also has fixed on it a ratchet wheel 7 with which is associated a disc 8 loosely mounted on the shaft. The

disc 8 carries pawls 9 adapted to co-act with the teeth of the wheel 7 and is provided with a slotted arm 10 with which is engaged the free end of a link 11 pivoted at 12 on the frame 13 of the loom.

At each side of the loom the slay has pivoted on it at 14 a lever 15 the shorter arm of which has connected to it one end of a spring 16 anchored on the slay at 17. The longer arm of the lever 15 carries a bowl 18 adapted to co-act with the cam 6, and the extremity of the lever arm has connected to it a weft lifter 19 adapted to reciprocate vertically in a guide 20, and the upper end 20^a of which is adapted to engage with the weft 21 as hereinabove described.

During the backward movement of the slay 4 from the beat up position shown in Fig. 2, the link 11 pulls on the arm 10 of the disc 8 and partially rotates the latter which 75 through the pawls 9 correspondingly rotates the cam 6 to disengage the cam surface 6^a thereof from the bowl 18 in the longer arm of the lever 15. The lever 15 then rocks on its pivot 14 under the influence of the spring 16 to raise the weft-lifter 19 which engages below the weft 21 and lifts same, as shown in dotted lines in Fig. 2, into the path of the weft-inserting needle 22 which picks up the weft and carries it into the warp shed.

During the subsequent forward or beat-up movement of the slay the disc 8 is partly rotated on the shaft 3 back to its original position, the pawls 9 over-riding the teeth of the ratchet wheel 7. During the next backward 90 movement of the slay the disc 8 is again operated to partly rotate the shaft 3 and cam 6 to engage the cam surface 6^b with the bowl 18 which depresses the lever 15 to pull down the weft-lifter 19 so that the latter does not 95 lift the weft which is consequently not taken by the weft-inserting needle during such movement of the slay.

It will be apparent that with the two cams at the opposite sides of the loom arranged 100 with their cam surfaces at 90° relatively to each other the two wefts will be alternately raised into the paths of the respective needles and carried into the warp sheds. It will also be apparent that by providing the cams 6 with 105 appropriate numbers of cam surfaces and arranging the cams with such surfaces in suitable relation to each other, the two wefts may be moved into the paths of the needles and carried by same into the warp shed simul- 110

taneously or in any other desired order instead of alternately, also that by providing more than two cams more than two wefts may be dealt with. For example, by providing the 5 cam at one side of the loom with four cam surfaces, and that at the other side with two cam surfaces, the weft at the first-mentioned side of the loom will be carried into the path of the corresponding needle and taken into 10 the warp shed at each pick while the weft at the other side will be taken into only alternate sheds as above described.

What I claim as my invention and desire to secure by Letters Patent is:—

- 15 1. In a shuttleless loom, a guide for presenting a weft thread to a weft inserter, said guide being mounted on the slay of the loom and adapted to be intermittently operated by the movement of the slay to interpose the weft 20 in the path of the weft inserter at the proper moment and afterwards carry the weft clear of the line of travel of the weft inserter.
- 20 2. In a shuttleless loom, means for presenting a weft thread to a weft inserter comprising

ing a guide member, a cam and ratchet wheel 25 adapted to be intermittently rotated, said guide being mounted on the slay of the loom and adapted to be operated by movements of the slay to interpose the weft in the path of the weft inserter at the proper moment and 30 afterwards carry the weft clear of the line of travel of said weft inserter.

3. In a shuttleless loom, means for presenting a weft thread to a weft inserter comprising a guide member, a cam and ratchet wheel 35 adapted to be intermittently rotated, a lever adapted to be operated by said cam against the action of a spring, said lever being operatively connected to said guide, said guide being mounted on the slay of the loom 40 and adapted to be operated by movements of the slay to interpose the weft in the path of the weft inserter at the proper moment and afterwards carry the weft clear of the line of travel of said weft inserter. 45

In witness whereof I have hereunto set my hand.

HUGH LINLEY BYRD.
